UNITED STATES PATENT OFFICE.

WILLIAM GOLDIE, OF PITTSBURG, PENNSYLVANIA.

DESIGN FOR A TIE-PLATE.

SPECIFICATION forming part of Design No. 30,852, dated May 23, 1899.

Application filed April 7, 1899. Serial No. 712,180. Term of patent 14 years.

To all whom it may concern:

Be it known that I, WILLIAM GOLDIE, a citizen of the United States, residing at Pittsburgh, county of Allegheny, and State of Pennsylvania, have invented and produced a new and useful Design for Tie-Plates, of which the following is a specification, reference being had to the accompanying drawing, forming part thereof, which shows a perspective view of the tie-plate embodying the design.

As shown in the drawing, the leading or material feature of my design consists of a tie-plate having a flat upper surface *a*, composed of thick rail-sustaining bar portions *b*, connected by thin webs *c*, the thick bar portions extending below the web portions and vertical tie-entering flanges projecting downwardly

from the thick bar portions. The plate has also the spike-holes *d*. As so constructed the tie-entering flanges enter the tie and hold thereto, while the rail rests upon the flat upper face of the plate and serves to brace the same, and the plate is forced down into the tie.

What I claim as being new, and desire to secure by Letters Patent, is—

The design for a tie-plate as herein shown and described.

In testimony whereof I, the said WILLIAM GOLDIE, have hereunto set my hand.

WILLIAM GOLDIE.
